Patented May 16, 1916.

UNITED STATES PATENT OFFICE.

HERMAN TORJESSEN, OF NEW YORK, N. Y.

PARTITION.

1,183,607.

Specification of Letters Patent.

Patented May 16, 1916.

Application filed February 7, 1916. Serial No. 76,598.

To all whom it may concern:

Be it known that I, HERMAN TORJESSEN, a subject of the King of Norway, residing in the borough of Brooklyn, county of 5 Kings, city and State of New York, have invented a certain new and useful Improvement in Partitions, of which the following is a specification, reference being had to the accompanying drawings, which form a part 10 of the same.

The object of my invention is to provide a partition formed of rails, stiles and panels and built in units so that the said partition may be erected wherever desired requiring 15 very little if any cutting at the places of erection.

In the drawings Figure 1 is a plan view partly broken away in places to show the construction of my partition; Fig. 2 is a 20 cross-section taken along the line 2--2 of Fig. 1; Fig. 3 is an enlarged detail view of a portion of Fig. 2; Fig. 4 is a cross-section taken along the line 4--4 of Fig. 1; Fig. 5 is a perspective view of the parts forming 25 a stile, which are shown in position and un-assembled; and Fig. 6 is a longitudinal end view of the stile shown in Fig. 5 in assembled condition; and Fig. 7 is a cross-section taken along the line 7--7 of Fig. 1.

Referring now in detail to the drawings, 30 13 and 14 represent tracks which are respectively secured along the line of a ceiling and floor between which a partition of my construction is to be built. A pilaster stile, 19 is secured to a wall 18 between the said tracks 13 and 14, from which wall it is intended 35 to build said partition. This pilaster stile consists of two pilasters having as many stiles 11 between them as it is desired to 40 have panels vertically arranged in the partition. For instance in the drawings accompanying this specification the partition is shown as being three panels in height which correspond to the number of stiles 45 between the pilasters used. These stiles are made of any shape for the purpose of accommodating the panels to be fitted thereto. For instance in the wooden panels 8 shown I have given the stiles a groove construc- 50 tion into which the wooden panels are fitted, whereas in the stiles shown for the glass construction 9 I have shown the faces

plain, preferring in these cases to secure the glass between the stiles by the use of beads 55 19 in the well known manner.

A pilaster stile having been fitted to the wall 18, rails 12 are inserted in the spaces 60 adjacent the ends of the pilaster stiles. The first tier of panels is then put into place adjacent the pilaster stile fitted to the wall 65 and between the rails 12 as shown, thus forming a three sided frame for each of the panels fitted into place. A second pilaster stile is slid into place, the spaces 70 16 thereof being fitted over the ends of the rails 12 and slid into place against the first tier of panels 8, 9 and 10, the spaces at the ends of the pilaster stile co-operating with the tracks 13 and 14 at the top and bottom of the partition. Additional panels are 75 added to the partition by repeating the operation described for the fitting of the first tier of panels and the method of such construction need not therefore be repeated.

In order to hold the panels, stiles and 80 rails in rigid position I connect and secure together the pilasters and rails by means of screws 17 or in any other desired manner. When the partition has been constructed as directed moldings 15 and 20 and base- 85 boards 21 may be inserted between or across the pilasters thus covering the longitudinal joint of the rails and giving a finished appearance to the partition.

While I have described a partition ex- 85 tending from a floor to a ceiling, still it will be obvious that a partition may be built from a floor to a point below the ceiling, the track 13 extending across the top of the partition rather than being connected with the ceiling.

In the above description and the accompanying drawings I have shown the preferable embodiment of my invention but I do not wish to be confined to the disclosure 90 therein contained but what I desire to cover by Letters Patent is set forth in the appended claims.

Claims:

1. In a partition consisting of panels, 100 rails and stiles, material strips, with stile sections therebetween spaced from each other and from the ends of such strips.
2. In a partition composed of panels,

rails and stiles, stiles provided with spaces adapted to slide on the said rails.

3. In a partition, a plurality of stiles having passages therethrough, rails adapted to fit into said stile passages and panels adapted to be fitted between said stiles and rails.

4. The method of assembling a partition consisting of stiles, rails and panels consisting of the erection of a stile having rail re-

cesses therein, the insertion of rails in said recesses, the sliding of panels in place between said rails and the sliding of recessed stiles over said rails. 10

HERMAN TORJESEN.

Witnesses:

JAMES N. CATLOW,
EVA GRACE MEHRINGER.
